Primary Examiner — Thomas Johannes*Assistant Examiner* — Shawn T Gingrich(74) *Attorney, Agent, or Firm* — Myers Bigel, P.A.(57) **CLAIM**

The ornamental design for a cabinet corner brace, as shown and described.

DESCRIPTION

FIG. 1 is an enlarged perspective view of a cabinet corner brace according to the present invention;
FIG. 2 is a side view thereof;
FIG. 3 is an opposite side view thereof;
FIG. 4 is a front view thereof;
FIG. 5 is a rear view thereof;
FIG. 6 is a top view thereof; and,
FIG. 7 is a section view thereof taken along lines 7-7 of FIG. 6.

The broken line portion of the figure drawings is included to show portions of the article that form no part of the claimed design.

1 Claim, 3 Drawing Sheets(56)
